(57) **CLAIM**

The ornamental design for a side rail for bed, as shown and described.

DESCRIPTION

FIG. 1 is a front perspective view of a side rail for bed taken from the left side thereof.

FIG. 2 is a front perspective view of the side rail for bed shown in FIG. 1 taken from the right side thereof.

FIG. 3 is a front elevational view of the side rail for bed shown in FIG. 1.

FIG. 4 is a rear elevational view of the side rail for bed shown in FIG. 1.

FIG. 5 is a top plan view of the side rail for bed shown in FIG. 1.

FIG. 6 is a right side elevational view of the side rail for bed shown in FIG. 1.

FIG. 7 is a left side elevational view of the side rail for bed shown in FIG. 1.

FIG. 8 is a front perspective view of another side rail for bed taken from the right side thereof.

FIG. 9 is a front perspective view of the side rail for bed shown in FIG. 8 taken from the left side thereof.

FIG. 10 is a front elevational view of the side rail for bed shown in FIG. 8.

FIG. 11 is a rear elevational view of the side rail for bed shown in FIG. 8.

FIG. 12 is a top plan view of the side rail for bed shown in FIG. 8.

FIG. 13 is a right side elevational view of the side rail for bed shown in FIG. 8; and,

(Continued)

FIG. 14 is a left side elevational view of the side rail for bed shown in FIG. 8.

The broken lines represent portions of the bed and form no part of the claimed design.
